Filed Dec. 30, 1963, Ser. No. 334,290
4 Claims. (Cl. 340—276)

This invention relates to an alarm system, primarily to a system for protecting a vault having an alarm bell outside the vault.

It is an object of the invention to provide a highly reliable alarm system. In carrying out the invention it is possible to achieve a stable system free of conventional balanced relays. The system can employ an oscillatory signal that is not easily measured.

The invention is illustrated by way of example in the accompanying drawings in which:

FIG. 1 is an electrical circuit diagram of apparatus that is located in a vault;

FIG. 2 is an electrical circuit diagram of a bell or alarm unit that is located outside the vault but is electrically connected to the unit of FIG. 1;

FIG. 3 is a plan view of a clock for the vault unit;

FIG. 4 is a partly sectional side view of the clock; and

FIG. 5 is an enlarged sectional view taken along the vertical plane indicated by the line 5—5 in FIG. 3.

The alarm unit of FIG. 2 can be mounted on an outside wall of a bank, preferably at a relatively inaccessible location. All parts of the unit are housed in a sealed box, from which a transmission line runs to the vault unit of FIG. 1, the line consisting of a pair of wires 10 and 11. The wires 10 and 11 normally carry an oscillatory signal from the vault unit to the remote alarm unit. As will presently be explained, when this signal is present a bell 13 (or other annunciator) in the alarm unit is prevented from ringing.

The wires 10 and 11 also conduct D.C. charging current to a six-volt battery 14 in the alarm unit. The D.C. flows to the battery through a choke 15, which impedes the oscillatory signal, and through a lamp 16. The lamp 16 is not employed to give a visual indication; rather it is a convenient electrical resistive means. Under normal conditions there is a D.C. voltage across the wires 10 and 11 substantially equal to the voltage of battery 14, so that only a small current flows through the lamp 16, the lamp is cold and its resistance is low. If, however, a short should occur across the wires 10 and 11, the lamp would have substantially full battery voltage connected across it, causing the lamp to heat rapidly. The lamp has a high temperature coefficient of resistance, and therefore its resistance quickly rises to place only a small load on the battery and prevent its rapid discharge. Consequently if a burglar should attempt to defeat the system by shorting the wires 10 and 11 he would not succeed in quickly discharging the battery to deprive the system of a power source for ringing the bell 13. If a high voltage were placed across the wires 10 and 11 with the object of destroying the battery, the lamp 16 would burn out and thereby protect the battery.

The oscillatory signal normally supplied over the wires 10 and 11 passes through a capacitor 17 to a resonant reed receiver 18. The signal causes reed contacts 19 to make and break alternately, thus supplying a pulsating D.C. output signal which is filtered by a capacitor 20 and resistor 21 and applied across an emitter-base resistor 22 of a transistor amplifier 23. This signal holds the transistor 23 on. A further transistor 24, biased by a resistor 25 and diode 26, is held off by the potential drop across resistor 27 when the transistor

2

23 is on. If the oscillatory signal supplied over the wires 10 and 11 disappears, the reed contacts 19 remain open, the transistor 23 goes off, the transistor valve 24 turns on, and current flows through a relay coil 28 to close relay contacts 29 and energize the bell 13 from the battery 14.

Now referring to the vault unit shown in FIG. 1, a power supply 30 is supplied from an A.C. line 31. The power supply 30 includes a rectifier and filter (not shown) for supplying six-volts D.C. across the wires 10 and 11 which run to the alarm unit of FIG. 2. A capacitor 32 is the final smoothing capacitor of the filter. The power supply 30 furnishes charging current for the battery 14 of the alarm unit and also supplies power for the vault unit, the sole battery in the system being the one in the alarm unit. This battery 14 supplies power for the whole system if the A.C. supply on line 31 should fail. Because charging current is supplied to the battery 14 over the wires 10 and 11, the battery can be relatively small and yet have a long life.

The oscillatory signal for the wires 10 and 11 is supplied by a tuning fork oscillator 33. Power for the oscillator is supplied by the power supply 30 through a choke 34 (which keeps the oscillatory signal out of the power supply) and through a coil 35 and diode 36. The oscillator is self starting, and thus generates an oscillatory signal as soon as it receives power. The signal from the oscillator passes through a capacitor 37 to the wire 10. It also passes through a capacitor 38, is rectified by diodes 39, 40 and filtered by a capacitor 41 and resistor 42, and applied across an emitter-base resistor 43 of a transistor amplifier 44. The signal holds the transistor 44 on. A further transistor 45, biased by a resistor 46 and diode 47, is held inoperative by the potential drop across resistor 48 when the transistor 44 is on. If the signal from the oscillator should momentarily fail (causing the bell 13 to ring), transistor 44 would turn off, causing transistor valve 45 to turn on. This shunts the oscillator 33 so that its signal remains off. The D.C. current through the coil 35 is increased. As will be more fully explained, the coil 35 is part of a timer and when actuated by the increased D.C. current it requires a predetermined time to elapse (for example, fifteen minutes, during which the bell 13 continues to ring) and then momentarily closes a switch 49. This supplies sufficient voltage to the oscillator 33 to resume its operation, so that the oscillatory signal can reappear to turn off the bell 13 and the transistor 45 and thus remove the D.C. which actuated the timer coil 35. A choke 50 prevents the oscillatory signal from being shunted through the oscillator when the switch 49 is closed.

If the line 10, 11 is momentarily opened, the oscillatory signal to the alarm unit is lost and the bell rings. The power supply 30 loses part of its load, and it is deliberately given poor voltage regulation so that its D.C. output voltage rises. This rise in voltage causes a Zener diode 51 to conduct, causing a voltage drop across a resistor 52 and thereby biasing the oscillator off. This causes the transistor valve 45 to be turned on, shunting the oscillator, so that the aforementioned predetermined time must again elapse before the oscillator can come on again. The amount of hum in the power supply 30 also changes if the line 10, 11 is open circuited, and this change in the operation of the power supply could, instead of its rise in voltage, be sensed to render the oscillator inoperative.

The vault unit has several switches 53a, 53b, 53c and 53d which are ganged together and which are moved to the position shown in FIG. 1 at times when the system is to be on guard against intruders. In series with the switch 53a is a door switch 54 which closes if an intruder

enters. This shunts the power supply 30 and the oscillatory signal, and the bell in the alarm unit rings as long as the switch 54 remains closed. When the switch 54 is reopened, the time delay required to charge the capacitor 41 prevents the transistor valve 44 from turning on before the transistor valve 45, so that in response to the resumption of power the latter transistor 45 turns on, actuates the timer coil 35, and holds the oscillator off until the timer closes the switch 49.

Another switch 53b connects a microphone 55 to the input of an audio amplifier 56. The amplifier is supplied with D.C. from the supply 30 through a choke 57 which blocks the oscillator output signal. A Zener diode 58, resistor 59 and capacitor 60 maintain a constant D.C. voltage supply to the amplifier so that the gain of the amplifier does not vary. The output of the amplifier passes through a capacitor 61 and is rectified by diodes 62 and 63 to turn off the transistor 44 in response to a noise picked up by the microphone 55. This turns on the transistor 45, which actuates the timer coil 35 and turns off the oscillator 33 until the predetermined time has elapsed. If desired the audio amplifier can include a short term memory circuit which requires a microphone noise signal that exceeds a given level or duration before turning off the transistor 44.

It will be apparent that the usual teller buttons, indicator lights and the like can be connected into the system by the switches 53c and 53d. A line can also be run to an alarm in the police station, to alert the police when the system is disturbed. Anti-tamper switches can be provided in parallel with the switch 54 to close if unauthorized persons seek access to the vault or alarm units.

FIGS. 3, 4 and 5 show a clock for operating the switches 53b, 53b, 53c and 53d. The clock has, within a casing 69 a conventional mechanically wound spring driven mechanism that will operate for at least fourteen days without rewinding. The mechanism can be wound by means of a shaft 70. A rotatable spindle 71 of the clock mechanism protrudes upwardly from the casing around the shaft 70. Around the spindle is a sleeve 72 keyed at 72a with the spindle to rotate therewith. Between a shoulder 73 near the lower end of the sleeve and a metal washer 74 near its upper end is a stack of metal discs numbered from 75 to 81. The washer 74 is held against the stack of discs by a clip 82 sprung into a groove of the sleeve. The discs 77 and 79 are not keyed to the sleeve, but the sleeve has a flat 72b to which the discs, other than 77 and 79, conform so that they must rotate with the sleeve. A nut 83, threaded onto the end of the spindle, is normally tightened down against the washer 74 to compress the stack and force the discs 77 and 79 to rotate with the sleeve and spindle. Thus the stack of discs forms part of the constantly driven mechanism of the clock. This mechanism rotates once every twenty-four hours in the direction of the arrow 84 in FIG. 3, and the top disc 81 has a dial 81a to show the time of day opposite a stationary pointer represented in FIG. 3 by an arrow 85, the time indicated in FIG. 3 being 9:00 a.m. If this time indicated should happen to be incorrect, knobs 86 on the disc 81 can be used to rotate the clock mechanism manually and set the correct time opposite the pointer 85. The disc 79 has an arm labelled D and the disc 77 has an arm labelled N. In FIG. 3 the arm labelled N (for night) is set at 6:00 p.m. and the arm labelled D (for day) at 6:00 a.m. For these settings the switches 53a to 53d are to be moved to the on guard position of FIG. 1 at 6:00 p.m. and are to be moved to their other, or off guard position, at 6:00 a.m. Thus, as the clock mechanism rotates from the time of day indicated in FIG. 3 (9:00 a.m.) to 6:00 p.m. the arm N comes opposite the pointer 85 and at the underside of the arm N a lug 87 comes into contact with a switch arm 88, forcing the arm 88 to pivot to the right about its axle 88a and moving the ganged switches 53a to 53d to the on guard position. At 6:00 a.m. the following morning (which

will be Thursday morning for the arrangement shown) the arm D comes opposite the pointer 85. The arm D is sufficiently long to contact a vertical pin 89, designated THUR. (for Thursday), mounted on an adjacent rotatable day wheel 90. The arm D by engaging the pin THUR. rotates the wheel 90 until the pin THUR. reaches approximately the position formerly occupied by the pin WED., i.e., a position opposite a stationary pointer 91, when the arm D is no longer long enough to continue engaging the pin THUR. and the wheel 90 ceases its movement. As the pin THUR. is moved by the arm D past the switch arm 88 (at 6:00 a.m.) it encounters the arm 88 and moves it to the left (i.e. to the position illustrated in FIG. 3), switching the system to the off guard condition. The pin SUN. is shown pulled up relatively to the other day pins on the wheel 90 so that when it is the turn of the SUN. pin to be moved by the arm D past the switch arm 88 the SUN. pin fails to strike the arm 88 and the system remains on guard, Sunday being a holiday. If however authorized persons planned to work in the bank on Sunday, the SUN. pin would be pushed down to a position like that shown for the other pins, and in its down position, as the SUN. pin was moved past the switch arm 88 (under the influence of the arm D at 6:00 a.m. Sunday), it would encounter the arm 88 and push it to the left, switching the system to the off guard condition. Thus, whether on a given day the system is to be off guard from 6:00 a.m. to 6:00 p.m. depends on whether the pin for that day is pushed down. The arm N ensures that the system is on guard every night from 6:00 p.m. to 6:00 a.m. The hours for which the arms D and N are set can be changed by loosening the nut 83 and rotating the arms to new positions relative to the dial markings 81a.

To ensure that the wheel 90 is properly positioned after the arm D disengages a pin, there is provided at the underside of the wheel 90 a detent 92 which is spring pressed upwardly to center in one of seven conical recesses 93 located radially inwardly from the pins. The detent 92, when centered in a recess 93, positions the wheel 90 correctly for the next engagement of the arm D with a day pin; when the arm D disengages a pin, it has pushed the wheel 90 slightly beyond this correct position so that next time around the arm D might jam or bind on the next pin, but the detent 92 by seating in a conical recess 93 pulls the wheel back to the correct position for the next engagement. Thus each day the wheel 90 is turned one seventh of a revolution by the clock mechanism. The pins are not easily removed from the day wheel, and spring pressed detents 94 which seat in necks 89a of the pins facilitate positive location of the pins in their pushed down or pulled up positions.

Below the lowermost disc 75 of the clock mechanism, and resting on a fiber washer 95, is a cup 96 having an inner hub 96a journaled on the spindle 71 and sleeve 72. Fixed within the cup, and coaxial with the disc 75, is the timer coil 35 which is connected into the circuit of FIG. 1 by flexible leads 97 (FIG. 3). When the coil 35 is not energized by current flowing through the transistor 45, the cup 96 rests on the washer 95, and an arm 96b fixed to the cup is held by a spring 98 against a stop 99 so that the cup is held stationary as the clock mechanism rotates. The cup 96 and the discs 75 and 76 are of magnetizable material, whereas the washer 95 is of non-magnetizable material. When the timer coil 35 is actuated by the transistor 45, the cup 96 and coil 35 are attracted to the discs 75 and 76 and move upwardly into close engagement with the disc 75 and begin to rotate therewith. Thus the cup 96 and coil 35 constitute an electromagnetic clutch that is engageable with the driven mechanism of the clock. After this clutch has rotated through an arc corresponding to a predetermined time of, say, fifteen minutes on the dial 81a, a contact 49a on the clutch arm 96b encounters a stationary contact 49b, closing the switch 49 of FIG. 1. As previously explained, this causes the coil 35 to be deactuated, so that the clutch disengages and the

spring 98 restores the clutch to its initial position where the arm 96b is held against the stop 99. Therefore whenever a disturbance puts the system into an alarm state, that state is maintained for at least fifteen minutes by the operation of the clutch. The contact 49b arrests the movement of the clutch, so that if for any reason the coil 35 fails to be deactuated when the switch 49 is closed, the clutch simply slips relative to the clock mechanism.

The disc 75 is thin and flexible and slightly distorted so that it does not lie perfectly flat against the disc 76. The disc 75 is also resilient, so that it presses the clutch downwardly to assist its disengagement. Part of the disc 75 is always touching the cup 96 to facilitate establishment of a good magnetic flux path through the cup 96 and discs 75 and 76 when the coil 35 is again energized; thus only a small amount of power is required to engage the clutch.

The electrical power requirements of the alarm system are not heavy, since the system is devoid of electromagnetic relays save for the relay 28 in the alarm unit, and this relay is not normally energized. Thus the single battery 14 can operate the system in the event of a failure of the power source that supplies the line 31. The transistorized circuits of FIGS. 1 and 2 are highly reliable, and the system is more stable and less costly than conventional alarm systems that employ balanced relays. The mechanically wound clock serves both to change the condition of the system from on guard to off guard and to move the clutch, so that the clutch and clock mechanism serve as a timer and no separately driven timer is required.

The oscillator 33 provides a signal of, say, 2500 cycles per second. Thus a burglar who does not have rather complex equipment cannot ascertain what type of signal is being transmitted by the wires 10 and 11 to prevent an alarm. He can readily measure the six volts D.C. across the wires 10 and 11 but if he connects a six volt battery across the wires 10 and 11, expecting that this will hold the bell inoperative, he will short out the oscillatory signal and cause the bell to ring. Even if he can measure the oscillatory signal he cannot easily replace it without special equipment and without knowledge of the alarm system circuitry. His task can be rendered still more difficult by using a signal device 33 and a receiver 18 capable of working at ultrasonic frequencies which cannot be heard by tapping earphones across the wires 10 and 11.

What I claim is:

1. An alarm system comprising an oscillator for supplying an oscillatory signal, an alarm at a location remote from the oscillator, a transmission line between the oscillator and the alarm for transmitting the oscillatory signal to the alarm, the alarm including a signal receiver responsive to the oscillatory signal to hold the alarm inoperative when supplied with the oscillatory signal by the line,

a battery at said remote location for operating the alarm, a direct current power supply located at the same end of the transmission line as the oscillator for providing a direct current voltage on the line, means connecting the battery to the power supply through the line for charging the battery by the power supply,

the receiver including means for rendering the alarm operative by the battery if the oscillatory signal is not received over the line and despite the presence of direct current voltage on the line, and disturbance responsive means for interrupting the supply of oscillatory signal to the line whereby the alarm is operated.

2. An alarm system as claimed in claim 1, wherein the oscillator has a direct current input normally supplied from the power supply but connected to the line for supply from the battery if the power supply fails.
3. An alarm system as claimed in claim 1, including a timer for maintaining the interruption of the oscillatory signal for a predetermined time interval, means for actuating the timer, the actuating means being normally held inoperative by the oscillatory signal, the timer being operative to restore said interrupted signal at the end of said interval.
4. An alarm system as claimed in claim 3, wherein the disturbance responsive means include means responsive to a change of load on the power supply to render the oscillator inoperative.
